UNITED STATES PATENT OFFICE.

ALBERT M. LEVERICH, OF MILWAUKEE, WISCONSIN.

GRINDING-WHEEL BEARING DISK.

Application filed September 14, 1923. Serial No. 662,718.

To all whom it may concern:

Be it known that I, ALBERT M. LEVERICH, a citizen of the United States, residing at Milwaukee, in the county of Milwaukee and 5 State of Wisconsin, have invented new and useful Improvements in Grinding-Wheel Bearing Disks, of which the following is a specification.

This invention relates to grinding wheels, 10 and more particularly to grinding wheel flanges, and an object of the invention is to provide a flange structure which will prevent the flying of parts of a grinding wheel in case the wheel is broken.

15 It is a well known fact, that frequently during the use of a grinding wheel it will break and with the present construction of flanges or disks used in bracing the wheel and connecting it to the driving shaft, the 20 pieces broken from the wheel are permitted to fly, during the rotation of the wheel often striking workmen and injuring them, and it is an object of the present invention to provide a novel, simple construction of flange 25 which will prevent the flying of the particles of the grinding wheel in that gripping members are carried by the flange which will move into tight binding or gripping engagement with a portion of the grinding wheel 30 in case the latter portion moves outwardly from the axis of the wheel.

Other objects of the invention will appear in the following detailed description taken 35 in connection with the accompanying drawings wherein:—

Fig. 1 is across section through a grinding wheel showing the improved flange associated therewith.

Fig. 2 is an enlarged detail section through 40 a part of the flange.

Fig. 3 is a section through a modified form of flange showing it applied.

Fig. 4 is a detail end view of the gripping member used in the modified form of the 45 invention.

Fig. 5 is a detail side elevation of the gripping member used in the modified form.

Referring more particularly to the drawings, a grinding wheel 1 of any approved 50 type, such as an emery wheel is shown which has clamped thereto the flanges or bearing disks 2 and 3. The bearing disks 2 and 3 are connected to the wheel 1 in the usual manner, preferably by means of screws, and 55 they are also provided with the usual form

of central bearing opening 4. The disk 2 is of the approved type, commonly in use having its flat inner surface bearing against the grinding wheel 1. The flange 3, however, is provided with cut out portions 5 at 60 circumferentially spaced points, extending inwardly from its inner surface, inwardly of the perimeter of the disk. The inner walls 7 of the recesses 5 incline inwardly towards the inner face of the disk as they extend outwardly towards its perimeter as clearly shown in Fig. 1 of the drawings. Gripping rollers 8 are mounted or placed in the recesses 5 and normally rest in the inner deep portion of the recesses. The rollers 8 are 70 substantially of the same diameter as the depth of the deep portions of the recesses 5 so that they will just engage the side of the grinding wheel 1. In case the grinding wheel breaks and a segment thereof loosens, 75 the rotation of the grinding wheel will cause the broken loosen section to move outwardly from the center of the wheel. On such outward movement, it will move the roller 8 outwardly therewith and the centrifugal 80 force created by the rotation of the wheel will cause a tight wedging action of the rollers 8 against the broken part of the grinding wheel and wedge it tightly against the flange 2 thereby preventing the broken part 85 from flying off.

In Figs. 3 to 5 of the drawings a modified form of the invention is shown in which the flange or disk 3' is provided with cut out portions 5' which are triangular shaped 90 in cross section and which have up-standing ridges 10 formed therein which engage in the longitudinally extending grooves 11 in the gripping blocks 12. The gripping blocks 12 replace the gripping rollers 8 and they are substantially frusto-pyramidal in shape being triangular in end elevation and substantially frusto-triangular in side elevation. The blocks 12 normally rest inwardly 95 in the inner deep portions of the cut out portions 5' and move outwardly into gripping engagement with the grinding wheel in case a portion of the wheel breaks and moves outwardly in the same manner in which the gripping rollers 8 cooperate to 100 prevent the broken part of the grinding wheel from flying outwardly.

It is, of course, to be understood that the invention may be constructed in other manners and the parts associated in different 110

relations and, therefore, I do not desire to be limited in any manner except as set forth in the claims hereunto appended.

Having thus described my invention what

5 I claim is:—

1. As a new article of manufacture, a bearing disk for grinding wheels provided with a plurality of recesses in its inner face, said recesses having their bottoms inclining 10 outwardly towards the inner face as they extend toward the periphery of the disk, and grinding wheel gripping members movably mounted in said recesses.

15 2. The combination with a grinding wheel, of a bearing flange having recesses in its inner face, said recesses having their bottoms inclined outwardly and gripping members movably mounted in said recesses.

20 3. The combination with a grinding wheel, of a bearing disk therefor provided with a plurality of recesses extending inwardly from its inner face and having their bottoms inclining inwardly towards the

inner face of the disk as they extend outwardly towards the periphery of the disk, 25 gripping rollers mounted in said recesses and normally out of gripping engagement with the grinding wheel, said rollers adapted to be forced into gripping engagement upon movement of any portion of the 30 grinding wheel outwardly from its axis.

4. The combination with a grinding wheel, of a bearing disk therefore, provided with a plurality of recesses extending inwardly from its inner face and having their 35 bottoms inclining inwardly towards the inner face of the disk as they extend outwardly towards the periphery of the disk, gripping blocks mounted in said recesses and normally out of gripping engagement with the 40 grinding wheel, said blocks adapted to be forced into gripping engagement upon movement of any portion of the grinding wheel outwardly from its axis.

In testimony whereof I affix my signature.

ALBERT M. LEVERICH.
